FRITZ BOHLE, OF CORRECTIONVILLE, IOWA.

LATCH.

1,192,105.

Specification of Letters Patent. Patented July 25, 1916.

Application filed March 22, 1916. Serial No. 85,962.

To all whom it may concern:

Be it known that I, WILLIAM PATTERSON, a citizen of the United States, residing at Correctionville, in the county of Woodbury 5 and State of Iowa, have invented certain new and useful Improvements in Latches, of which the following is a specification.

This invention relates to latches and has for its object the provision of a simple device which may be operated from either side 10 of a door to lock the latch against accidental release.

A further object of the invention is to provide means whereby a pivoted latch may be 15 locked in engagement with a hasp or keeper by movement of the knob spindle and the knob spindle locked against movement except upon positive manual manipulation.

The invention seeks to provide a device 20 for the stated purpose which will be free of complicated arrangements or structures and which may be produced at a low cost and easily repaired or parts replaced.

One form of the invention is illustrated 25 in the accompanying drawings and the invention resides in certain novel features which will be hereinafter fully described and then particularly pointed out in the claims following the description.

30 In the drawings: Figure 1 is a view partly in elevation and partly in section of a latch embodying my invention with one side plate of the casing removed and showing the latch in engagement with the hasp;

35 Fig. 2 is a similar view showing the position of the parts when the latch is locked out of engagement with the hasp; Fig. 3 is a vertical section taken through the knob spindle and showing the parts in an intermediate position; Fig. 4 is a detail view of 40 a part of one face plate of the casing.

In carrying out my invention, I employ a casing in which one face plate 1 is preferably constructed with a flange 2 extending 45 around all the edges of the said plate, and a second face plate 3 is adapted to rest against the edge of said flange. The flange 2 forms the top, bottom and ends of the lock casing and in the outer end of the same 50 is provided a vertical slot 4 through which the end of the latch 5 projects and plays. The side or face plates 1 and 3 are permanently secured together by means of screws or bolts inserted through the same and supported by bosses 6 at the corners of the 55

casing. The face plates are provided with registering openings 7 and in the said openings are fitted bushings 8 which receive and support the knob spindle 9 and on the inner ends of said bushings are annular flanges 10 which fit against the inner surface of the face plates and thereby prevent withdrawal of the bushings and also guard against entrance of dust or other foreign matter into the casing. Suitable knobs or handles of 60 any desired form are to be secured upon the ends of the knob spindle which is angular in cross section, as shown clearly in Figs. 1 and 2, and is also slidable longitudinally in the bushings 8 which constitute the journals 70 for the spindle in its rotary movement within the casing.

The latch 5 is provided at its outer end with a hook 12 adapted to engage a hasp or other form of keeper, indicated at 13 in dotted lines, and secured to the side of the barn or other building immediately adjacent the door opening, it being understood that the lock casing may be secured to the door in any well known manner. The inner end of 80 the latch 5 is pivotally mounted upon a stud 14 which is secured to or formed integral with the inner side of the face plate 1 and said stud is provided with an annular enlarged portion 15 which serves to hold the 85 latch spaced from the said face plate and in proper position to have its outer end play in the slot 4 without excessive wear upon the contacting surfaces.

Above and below the latch are freely 90 mounted slidable locking bars 16 which have their outer ends arranged to bear respectively upon the upper and lower edges of the latch and constructed with reduced terminals 17 adapted to enter the slot 4 and fit snugly between an end of the same and the adjacent edge of the latch so as to wedge the latch in the opening and thereby hold it in either its raised or lowered position, as will be readily understood. These 100 locking bars are guided in their longitudinal movement by rollers 18 which are mounted on suitable pins 19 carried by the face plate 1 and arranged above the upper bar and below the lower bar, as clearly 105 shown. The inner extremities of the locking bars are reduced, as shown at 20, so as to permit the ends of cranks 21 to fit between the bars and the face plate 3, and these cranks 21 are pivotally attached to 110

the inner ends of the locking bars by studs 22 projecting from the cranks and engaging sockets 23 in the bars. These studs may be cylindrical lugs formed on the cranks or 5 may be pins inserted through and secured rigidly in the cranks, as will be readily understood. The locking bars bear at one side against the face plate 1 and on their opposite sides are provided with lateral lugs 10 24 which bear against the face plate 3 and serve as guides or retainers to hold the bars in proper position to enter the slot 4 without having an extended bearing upon the said face plate and, consequently, creating 15 excessive friction. The cranks 21 are preferably formed integral with a central enlargement or disk 25 which is fitted upon the knob spindle and shrunk or otherwise secured thereto so that the cranks will follow 20 all the movements of the spindle. The cranks 21 are also provided in their outer sides with sockets 26 which are adapted to engage pins or studs 27 on the face plate 3 and thereby hold the cranks against movement 25 in a transverse plane of the knob spindle, and such engagement is normally and yieldably maintained by a spring 28 which is coiled around the spindle between the inner side of the disk or enlargement 25 and the adjacent bushing 8.

The construction and arrangement of the several parts of my device being thus made known, it is thought that the operation will be readily understood. If it be desired to 35 turn the knob spindle, the tension of the spring 28 must obviously be first overcome, and this operation is effected by exerting a push or a pull upon one of the knobs or handles accordingly as to whether the latch 40 is to be operated from the inside or outside of the door. The force thus exerted upon the knob or handle will effect longitudinal movement of the knob spindle and thereby compress the spring 28 and, inasmuch as 45 the cranks 21 will follow the movement of the knob spindle, the sockets 26 will be withdrawn from their engagement over the pins or studs 27 so that the knob spindle can then be rotated and the cranks moved 50 past the said pins.

Assuming that the latch is in the position shown in Fig. 1, and that it is desired to withdraw the same from its engagement with the hasp, the spindle is rotated in such direction that the upper locking bar 16 will be moved inwardly while the lower bar will be moved outwardly. The lower crank 21, connected with the lower locking bar, will 55 positively swing downwardly as well as outwardly and this movement will cause the bar to ride upon the roller 18 outwardly and upwardly toward the latch and lift the same, as shown in Fig. 2, the upper bar being simultaneously withdrawn from the slot 60 4 and away from the outer end of the latch

so that the latch may move upwardly in the said slot.

In the position shown in Fig. 1 the end of the upper locking bar fills the slot 4 between the upper end of the same and the upper edge of the latch 5 which rests upon the lower end of the slot and accidental upward releasing movement of the latch is thereby prevented. As the upper locking bar recedes, the latch, of course, is free to rise and will rise under the lifting force exerted against the same through the lower locking bar which will move to such a position that its extremity enters the slot 4 and fills the same between its lower end and the under edge of the latch, as shown in Fig. 2. In this position of the parts, the latch will be locked out of engagement with the hasp and positively held against accidental reengagement. It will be noted upon reference to Fig. 4 that there are six pins 27 upon the face plate 3, the said pins being arranged three above and three below the center of the knob spindle and each pin being diametrically opposite another pin. When the 70 cranks 21 are in engagement with the central pins, the parts will be in an intermediate position between the position illustrated in Fig. 1 and that illustrated in Fig. 2, so that the latch will be ready to engage 75 the hasp but will not be engaged with it and the locking bars will be in such position that a slight movement in the desired direction will lock the latch in either its raised or lowered position. When the 80 cranks are in either of the positions illustrated in Figs. 1 and 2, the pins 27 at the ends of the series or sets of pins, will engage the sockets in the cranks and will thereby hold the knob spindle against rotation so 85 that accidental release of the latch will be 90 prevented.

From the foregoing description it will be readily noted that I have provided an exceedingly simple device which may be produced at a low cost and which is not apt to 95 get out of order. The upper locking bar is held in engagement with the latch by the force of gravity and the roller 18 bearing thereon will prevent the locking bar swinging away from the latch during movement 100 of the crank 21 pivoted thereto, while the lower locking bar is so positioned relative to the roller 18 that it is prevented from dropping to an inoperative position by said 105 roller and, as it is actuated through the movement of the crank pivoted thereto, will be directed against the latch. The studs 22 will, of course, be long enough to remain in 110 engagement with the openings 23 in the locking bars in all positions of the knob spindle and the cranks so that the dropping 115 of the inner ends of the locking bars away from the cranks will not occur and the device will consequently always be in opera- 120 125 130

tive condition. The spring 28 will automatically cause the cranks to engage the pins 27 when the knobs are released so that the liability of leaving the door unlatched is minimized.

Having thus described the invention, what is claimed as new is:

1. The combination of a lock casing, a latch pivoted in and projecting through the same, locking bars mounted freely in the casing above and below the latch and adapted to engage the casing respectively above and below the latch whereby to lock the latch in a set position, and means for operating said locking bars.

2. The combination of a casing, a latch pivotally mounted in the casing and projecting through the same, locking bars mounted freely in the casing above and below the latch and adapted to engage opposite sides of the same, means within the casing to guide the said locking bars into engagement with the casing at the side of the latch whereby to hold the latch in a set position, and means for imparting movement to the locking bars simultaneously in opposite directions.

3. The combination of a casing, a latch pivoted to and projecting through the casing, a knob spindle mounted in and extending through the casing, locking bars disposed above and below the latch, and connections between the knob spindle and the locking bars whereby to cause either of said locking bars to engage between the latch and the casing to hold the latch in a set position.

4. The combination of a casing, a latch pivoted therein and projecting therethrough, locking bars mounted within the casing above and below the latch, a knob spindle mounted in and extending through the casing, said knob spindle having a longitudinal sliding movement and also a rotary movement, connections between said knob spindle and the locking bars whereby either locking bar may be caused to engage between the latch and the casing to hold the latch in a set position, means for yieldably holding the spindle against sliding movement, and means for positively holding the spindle against rotary movement.

5. The combination of a casing having a slot in one end, a latch pivoted within the

casing and projecting through said slot, locking bars mounted freely within the casing above and below the latch, and means for causing the outer end of either tumbler to fill the slot in the casing between the end of the same and the side of the latch whereby to hold the latch in a set position.

6. The combination of a casing, a latch pivoted in and projecting from the casing, locking bars mounted in the casing above and below the latch and adapted to engage between the latch and the casing, a knob spindle slidably and rotatably mounted in the casing, cranks fixed upon the said spindle and having a sliding pivotal engagement with the inner ends of the locking bars, means for yieldably holding the spindle against sliding movement, and interengaging means on the casing and cranks to hold the spindle against rotary movement.

7. The combination of a casing, a latch pivoted in and projecting from the casing, locking bars disposed within the casing above and below the latch and adapted to engage between the latch and the casing to hold the latch in a set position, a plurality of internal projections on one side of the casing, a knob spindle slidably and rotatably mounted in the casing, cranks fixed to said spindle and provided on their inner faces with studs having slideable pivotal engagement with the inner ends of the locking bars, the cranks being further provided in their outer faces with sockets adapted to engage the projections on the side of the casing, and means for yieldably holding the spindle against sliding movement.

8. The combination of a casing, bushings rotatably fitted in the opposite sides of the casing, a knob spindle slidably fitted in said bushings, cranks fixed upon the spindle adjacent one of the bushings, a spring coiled around the spindle between said cranks and the other bushing, a latch pivoted in and projecting through the casing, locking bars mounted within the casing above and below the latch, slideable pivotal connections between the locking bars and the cranks, and interengaging means on the cranks and the casing to prevent rotary movement of the cranks and the spindle.

In testimony whereof I affix my signature.

WILLIAM PATTERSON. [L.S.]
